John H. DePeler

ATTORNEY.

UNITED STATES PATENT OFFICE.

JOHN H. DEPELER, OF WEEHAWKEN, NEW JERSEY, ASSIGNOR TO THE HEAT RESEARCH AND SERVICE CORPORATION, OF WILMINGTON, DELAWARE, A CORPORATION OF DELAWARE.

THERMAL MINE.

Application filed November 2, 1926. Serial No. 145,866.

The invention relates to certain improvements in thermal mines or bombs of the general character disclosed in Patent No. 1,562,137, dated November 17, 1925, and application Serial No. 107,300, filed May 6, 1926, and has for its object to provide a shell or casing for the thermit charge, in which the relation of the bottom of the casing to the body thereof is such that the bottom only will burn out and release the superheated reaction products as soon as the reaction has progressed completely from the top to the bottom of the thermit mass; whereby the molten mass will be liberated as an entirety in a localized zone or area and the efficiency of the charge increased enormously thereby.

The invention is illustrated in the accompanying drawings, in which:—

Fig. 1 is a broken sectional elevation of a thermal mine involving the invention.

Fig. 2 is a similar view showing a modified form of shell or container.

In practicing the method of loosening ice accumulations, as disclosed in the Letters Patent aforesaid, and in similar operations involving the use of thermit or analogous charges, it has been found that, unless means are provided for liberating the products of the thermal reaction as soon as such reaction is completed, the results are not altogether satisfactory, as much of the superheat of the reaction is dissipated too slowly throughout the surrounding mass of ice and the like, or, in other cases, the walls of the container will be burned through at various places during the progress of the thermal reaction, thereby liberating relatively small portions of the superheated charge, which are practically ineffective to produce any material results on the ice or other body acted upon. It has also been conclusively demonstrated that, if the container for the thermit charge is so constructed that it will burn through at one place only, for example, the bottom thereof, as soon as the exothermic reaction has been completed, the entire superheated mass of metal and slag will be discharged in an entirety in a highly localized zone or area, so that the working efficiency of the mine or bomb will be very largely increased.

To effect this result, it is sufficient to construct the body of the container of such materials and proportions as will be practically unaffected by the heat of the reaction and to

provide a bottom for the container of material that will burn out and be consumed immediately the thermal action has been completed; that is to say, as soon as the reaction has progressed from the top of the thermit mass to the bottom thereof.

A relatively simple, but highly efficient form of shell or container within the scope of the invention is illustrated in Fig. 1, in which 1 is the body portion of the shell or casing, which is preferably made of iron or steel of relatively heavy gauge, which in a bomb containing one hundred pounds of thermit may be one quarter of an inch thick.

The top 2 of the casing, which may be of similar thickness, is provided with a screw threaded opening 6, which receives a threaded plug 7 supporting the ignition device, of the type described in the patent aforesaid, said ignition device being embedded in the charge of thermit, which substantially fills the shell or casing. The bottom of the shell or casing, which may be formed integrally with the body portion or secured thereto by any appropriate means, is preferably made of relatively thin material, so that it will burn out or be completely consumed in the heat of the reaction, when the thermit charge has been ignited, so that the entire resultant molten mass, representing the products of the reaction, will be discharged as an entirety from the lower end of the casing, whereby the effects of the great superheat of the charge will be localized and the efficiency of the mine greatly increased.

The exact thickness of the bottom is not material, provided it is such that the bottom alone will burn out, when the thermal reaction has been completed. In the case of the one hundred pound mine hereinbefore referred to, the bottom of one-eighth inch steel gives excellent results and burns away completely immediately the thermal reaction has progressed to completion, while the relatively thick side walls and top of the casing are practically unaffected by the heat of the reaction.

Instead of making the side walls of the container of relatively thick metal or other material, as compared with the bottom, the same desirable result may be obtained by making the container of substantially the same uniform thickness as to its walls and bottom, but providing the walls with a lining

of heat insulating material, such as sheet asbestos, as illustrated in Fig. 2, in which 1' represents the wall of a generally cylindrical container, preferably formed of sheet steel, 5 the interior walls being covered or lined with a sheathing of asbestos, or similar heat insulating material 4. In this case, the bottom 3' may be made of the same material and same thickness as the walls 1, but the side walls are 10 protected from the effects of the superheat of the reaction by the insulating lining 4, so that the reaction may proceed downward to completion without impairing the side walls, and as soon as the reaction has been 15 completed and the molten mass comes in contact with the bottom 3', the latter will be burned away instantly, thereby releasing the entire products of the reaction.

What I claim is:

- 20 1. A thermal mine comprising a casing for containing a thermit charge having a body

portion comparatively unaffected by the heat of the thermal reaction and a bottom which burns out and releases the charge when the reaction is complete.

25

2. A thermal mine comprising a casing for containing a thermit charge having a body of sufficient thickness to be comparatively unaffected by the heat of the thermal reaction, and a bottom adapted to burn out and 30 release the charge when the reaction is complete.

3. A thermal mine comprising a casing for containing a thermit charge having a metal body portion of sufficient thickness to be comparatively unaffected by the heat of the thermal reaction and a relatively thin metal bottom adapted to burn out and release the 35 charge when the reaction is complete.

In testimony whereof I affix my signature.

JOHN H. DEPPELER.
